UNITED STATES PATENT OFFICE.

EDWIN GUSTAVE STAUDE, OF MINNEAPOLIS, MINNESOTA.

COUNTER FOR BLANKS.

1,154,451.

Specification of Letters Patent. Patented Sept. 21, 1915.

Application filed May 7, 1912. Serial No. 695,718.

To all whom it may concern:

Be it known that I, EDWIN G. STAUDE, of Minneapolis, Hennepin county, Minnesota, have invented certain new and useful Improvements in Counters for Blanks, of which the following is a specification.

My invention relates to counting devices for blanks of various kinds, such as flexible box blanks, and envelop blanks, and the object of the invention is to simplify and improve the apparatus shown and described in my pending application for Letters Patent of the United States, Serial No. 522,198, filed October 11, 1909.

The invention consists generally in various constructions and combinations, all as hereinafter described and particularly pointed out in the claims.

In the accompanying drawings forming part of this specification, Figure 1 is a vertical sectional view through a blank forming machine with my improved counting mechanism mounted thereon, Fig. 2 is a detail sectional view showing the side elevation of the counting mechanism and the means for operating the counter disk, Fig. 3 is a detail view of the mechanism removed from the machine, showing the means actuated by the passage of a blank for operating the escapement mechanism, Fig. 4 is a detail sectional view showing the crank on which the blank actuated roll is mounted, Fig. 5 is a top view of the counter mechanism, Fig. 6 is a vertical sectional view, showing the means for operating the ratchet wheel or disk, Fig. 7 is a sectional view on the line $\alpha-\alpha$ of Fig. 6.

In the drawing, 2 represents the frame of the machine and 3 and 4 feed belts between which the blanks are fed to the counting mechanism.

5 is a hopper having a suitable feed device, such as a belt 6, and 7 is a spiral by means of which the blanks are fed into the hopper from the bottom. This hopper and the feeding means therefor are shown and described in Letters Patent of the United States, No. 1,018,087, issued to me February 20, 1912.

8 is the device I prefer to employ for indenting the pile of blanks, that is, retarding one or more of them at predetermined intervals to divide the pile into groups, each of a predetermined number of blanks. This indenting device is shown and described in Letters Patent of the United States, No. 961,263, issued to me June 14, 1910.

The counting mechanism in a general way, particularly the parts actuated by the passage of a blank, is substantially the same as that shown and described in my pending application above referred to, my present invention relating to features which are designed to simplify and improve the mechanism of said application with a view of making the counter more efficient and more reliable.

9 is a transverse shaft having a gear 10 thereon which meshes with a piston 11 that is carried by a bracket or hanger 12. The piston 11 meshes with a pinion 13 secured on a shaft 14 that is journaled in the bracket 12 and has a roller 15 secured thereon. The roller 15 is provided at one end with a series of teeth 16 meshing with teeth 17 of a roller 18 that is preferably smaller than the roller 15 and provided with a narrower face and is mounted on a shaft 19 carried by a crank 20 which is secured to a rock shaft 21 journaled in the bracket 12. An idle gear 22 is mounted on the shaft 21 and meshes with the pinion 13 and is driven thereby and the hub of said idle gear has a worm 23 thereon meshing with a worm gear 24 that is secured to the lower end of an upright shaft 25 which also has bearings in the bracket 12. (See Fig. 2.)

The feed belts 3 and 4 pass around pulleys or wheels 26 and 27 on the shafts 9 and 28 and deliver the blanks to the rolls 15 and 18, as will hereinafter appear. The upper portion of the bracket 12 has a horizontal extension forming a flange 29 and a slide 30 is arranged to reciprocate on said flange and is provided with an opening 31 to receive the shaft 25 and a hub 32 that is secured to the said shaft and is provided at its upper end with a disk 33. This disk has an upper bearing plate 34 secured to the disk by rivets or other suitable means and near the upper end of the shaft a disk 35 is mounted to slide on said shaft by means of a feather or spline 36, and is provided on its under surface with a bearing plate corresponding to the one described. A spring 37 holds the disk 35 downward with a yielding pressure, the tension of the spring being regulated by an adjusting nut 38. A ratchet wheel 39 is interposed between the disks 33 and 35 and a plate 40 is secured to said wheel by screws or other suitable means and has a peripheral cam surface 41 terminating in a shoulder 42 upon which a lug 43 is pre-

erably mounted. The ratchet wheel and plate 41 are free to turn on the shaft 25 against the frictional engagement of the bearing plates 34 therewith, the degree of this frictional engagement being regulated by the tension of the spring 37. The slide 30 is free to move a limited distance, and upon this slide I mount lugs 44 and 45 provided with wedge-shaped faces 46 and 47 which are adapted to pass between the teeth of the ratchet wheel. The distance between the inner edges of these wedge-shaped faces is less than the diameter of the ratchet wheel and consequently when one wedge face is moved out of engagement with a tooth of the ratchet wheel, the opposite wedge face will be moved into engagement with a tooth on the opposite side of the wheel, as shown plainly in Fig. 6, thus constituting in effect, an escapement mechanism to control the movement of the ratchet wheel.

From an examination of Fig. 6 it will be evident that the continuously revolving shaft 25 will form a positive drive for the disks 25 33 and 35 and the frictional engagement of the bearing plates of these disks with the ratchet wheel will operate it also with a step-by-step movement when the slide 30 is reciprocated, the wheel moving one step or 30 tooth with each stroke of the slide. To operate the slide I prefer to provide a lug 48 thereon at one end fitting within a recess 49 formed in the jaws 50 of a lever 51. The end of this lever is preferably split to form 35 the jaws and is provided with an adjusting bolt 52 passing through the jaws and by means of which the walls of the recess 49 can be adjusted with respect to the lug 48 to take up wear or lost motion. An arm 53 40 is secured on the shaft 21 and is provided with a recess to receive the lever 51 which is preferably mounted at a point intermediate to its ends on a pivot pin 54 carried by the upper portion of said arm. A pin 55 45 fits loosely within a hole 56 in the lower portion of the arm and passes through the lower end of the lever 51, and tension springs 57 are connected to the ends of said pin. These springs allow the lever 51 to 50 swing on its pivot and accommodate itself without changing its stroke to any variation in the thickness of the blanks passing between the rollers 15 and 18. An adjusting screw 58 is mounted in the arm 53 and engages the lower portion of the lever 51 for the purpose of adjusting it and regulating the movement of the slide 30. The arm 53 is rocked by the movement of the roll 18 when a blank passes between it and the roll 60 15 against the tension of a spring 59.

60 is a lever pivoted at 61 and connected at its lower end to a tension spring 62 which tends to pull the upper end of the lever 60 in toward the ratchet wheel and hold the 65 arm 63 carried by said lever in contact with

the peripheral cam surface 41 on the plate 40. The upper end of the lever 60 has a stud 64 mounted therein provided with a socket in which a rod 65 is adjustable lengthwise by means of a set screw 66. The stud is also 70 capable of rotation in its bearings in the lever to raise or lower the end of the rod 65 for convenience of attachment to the part 8, as illustrated in Fig. 1. Normally the rod 65 will hold the part 8 out of the path of the blanks, the arm 63 riding on the cam surface of the disk 41, but when the arm 63 reaches the shoulder 42 and drops off the high part of the cam the tension of the spring 62 will pull the rod 65 lengthwise 80 and swing the part 8 into the path of the incoming blanks, retarding one or more of them and forming an inset in the pile of blanks.

The lever 60 operates with each revolution 85 of the ratchet wheel and the number of teeth in the ratchet wheel determines, therefore, the time of operation of this lever. I prefer to provide twenty-five of them so that the lever 60 will operate the retarding mechanism and divide the pile of blanks into groups of twenty-five, which number can be handled conveniently. Of course, the operation of the retarding mechanism can be modified to increase or decrease the number 95 of blanks in each group.

I also prefer to provide a registering device in connection with the counter indicated at 67 and provided with a star wheel 68 in the path of the lug 43, so that with 100 each revolution of the ratchet wheel the lug will operate the star wheel and the registering mechanism. The slide 30 is limited in its reciprocating movement by the engagement of a shoulder 69 formed on the slide with the end walls of a recess 70 in the flange 29, and a lug 71 formed on the end of the slide is adapted to contact with the edge of the flange, thereby positively limiting the stroke of the slide in both directions. Feed rollers 72 and 73 are located near 105 the rollers 15 and 18 to receive the blanks therefrom and direct them to the hopper feeding belt.

In the operation of the device, the blanks are fed between the rolls 15 and 18 by the feed belts 3 and 4 and the passage of the blanks between the rolls will rock the crank 20 and oscillate the arm 53 to move the lever 51 outwardly. The outward movement of this lever will withdraw the lug 45 from engagement with a tooth of the ratchet wheel and the same movement will move the lug 44 into engagement with a ratchet wheel tooth. It is evident from an examination of Fig. 7 that the lug 44 will engage the face of the ratchet wheel tooth corresponding to the face of the tooth on the outer side of the wheel engaged by the lug 45, and as the ratchet wheel turns in 130

the direction of the arrow it will be evident that when the lug 45 is withdrawn from the wheel to allow it to be turned that it will be free to revolve a sufficient distance before engaging the lug 44 to allow the lug 45 to enter the next notch in the wheel on its return stroke. The revolution of the wheel having been completed, the counter mechanism will operate in the manner described and actuate the indenting device to retard the blanks and divide the pile into groups, each of a predetermined number of blanks.

I claim as my invention:

- 15 1. The combination, with a ratchet wheel, and means for operating the same, of a slide having lugs to engage the teeth of said wheel, a lever pivotally connected with said slide, a rocking arm having a recess wherein said lever is pivoted at a point intermediate to its ends, means yieldingly resisting the oscillation of said lever in said recess, means for positively limiting the stroke of said lever, and means actuated by the passage of 25 a blank for rocking said arm.
2. The combination, with a standard having a flanged upper end and a shaft journaled therein, of a ratchet wheel loosely mounted on said shaft, means secured on 30 said shaft and having frictional engagement with said ratchet wheel for turning the same, a slide arranged to reciprocate on said flanged end and having lugs to engage the teeth of said ratchet wheel, and means 35 actuated by the movement of a blank for reciprocating said slide to alternately engage said lugs with the teeth of said wheel.
3. In a counting mechanism comprising rotatable members one of which has 40 continuous movement and the other intermittent movement, stop-mechanism for holding the intermittently moving member and including a pawl and ratchet escapement operatively connected with the intermittently moving member, and means adapted to be operated by a box-blank and operatively connected with the pawl and ratchet escapement to engage one pawl of the escapement with the ratchet as the other pawl 45 is disengaged from the ratchet, substantially as described.
- 50 5. In a counting mechanism comprising rotatable members, stop-mechanism for holding one of said members from continuous movement and including a pawl and ratchet escapement operatively connected with said member, a pair of continuously revoluble rolls arranged for the passage of a box-blank between them, and means connecting one of said rolls with the pawl and ratchet escapement to engage one pawl of 55 the escapement with the ratchet as the other pawl is disengaged from the ratchet, substantially as described.

4. In a counting mechanism comprising rotatable members one of which has continuous movement and the other intermittent movement, stop-mechanism for holding 55 the intermittently moving member and including a ratchet wheel connected with the intermittently moving member and a slideable bar having teeth to alternately engage the ratchet wheel, and means adapted to be 60 actuated by a box-blank and operatively connected with said bar to reciprocate the same to bring its teeth in alternation into engagement with the ratchet, substantially as described.

6. In a counting mechanism comprising rotatable members, stop-mechanism for holding one of said members from continuous movement and including a pawl and ratchet escapement operatively connected 70 with said member, a pair of continuously revoluble rolls arranged for the passage of a box-blank between them, and means connecting one of said rolls with the pawl and ratchet escapement to engage one pawl of 75 the escapement with the ratchet as the other pawl is disengaged from the ratchet, substantially as described.

7. In a counting mechanism comprising rotatable members, stop-mechanism for holding one of said members from continuous movement and including a pawl and ratchet escapement operatively connected with said member, parallel shafts each carrying a revoluble roll, one of said shafts being a crank-shaft and operatively connected with the pawl and ratchet escapement to engage one pawl of the escapement with the ratchet as the other pawl is disengaged from the ratchet, a pinion and worm mounted on 80 the crank-shaft, and an upright shaft connected with said rotatable members and provided with a worm-gear meshing with the worm of the crank-shaft, substantially 85 as described.

In witness whereof, I have hereunto set my hand this 2nd day of May, 1912.

EDWIN GUSTAVE STAUDE.

Witnesses:
